Primary Examiner — Charles Hanson*(74) Attorney, Agent, or Firm* — Knobbe Martens Olson & Bear, LLP(57) **CLAIM**

The ornamental design for a wheelchair, as shown and described.

DESCRIPTION

FIG. 1 is a left side view of a wheelchair embodying my new design, the right side view forming a mirror image thereof.

FIG. 2 is a front view thereof.

FIG. 3 is a back view thereof.

FIG. 4 is a top view thereof.

FIG. 5 is a front perspective view thereof; and,

FIG. 6 is a detail, front perspective view of a footrest portion of the wheelchair of FIG. 1.
